CUSHION CONSTRUCTION

Filed May 14, 1926

FIG. 1.

FIG. 2.

FIG. 3.

Inventor.

Frank Kaspar

By Raymond, Lee, Clinton, Miller & Abbott

UNITED STATES PATENT OFFICE.

FRANK KASPAR, OF CHICAGO, ILLINOIS, ASSIGNOR TO S. KARPEN & BROS., OF CHICAGO, ILLINOIS, A CORPORATION OF WEST VIRGINIA.

CUSHION CONSTRUCTION.

Application filed May 14, 1926. Serial No. 109,079.

This invention relates particularly to cushions adapted for automobile purposes, for sleeping car purposes, or the like.

The primary object is to provide an improved cushion of staunch construction which possesses important advantages from the standpoint of comfort and from the standpoint of durability.

The present invention constitutes a modification of the invention described in my pending application Serial No. 109,078, filed of even date herewith.

The invention is illustrated in its preferred embodiment in the accompanying drawing, in which—

Fig. 1 represents a broken plan view of the improved cushion; Fig. 2, a broken sectional view taken as indicated at line 2 of Fig. 1; and Fig. 3, a broken inner face view of the cushion-bottom.

In the embodiment illustrated, the cushion comprises a rectangular base-frame A which supports a bottom A'; a marginal row of upholstery springs B supported on the frame A and connected at their upper ends with a marginal rod B'; an inner body of upholstery springs C supported on the bottom A', the upper ends of the marginal row of the inner or main body of springs being connected with a marginal rod C'; a filling of suitable stuffing, or wadding, material D, such as hair, moss or cotton, disposed above the springs; and a covering E which may comprise a ply of burlap 1 and a finish-fabric 2.

The outer marginal row of springs B preferably are enclosed in individual pockets, or coverings, of fabric 3; and the springs are united at their upper ends by ties, or 40 stitches, 3^a. The springs B are also connected with the marginal rod B' as by means of ties, or stitches, 3^b.

The springs C of the main body of springs preferably are encased in individual fabric 45 containers 4. These springs are longer than the springs of the outer marginal row B, and preferably are somewhat lighter. The springs C are connected at their upper ends by ties, or stitches, 4^a; and the springs of the 50 marginal row of the main body of springs are connected with the marginal rod C' by ties, or stitches, 4^b.

The base of the structure comprises the rectangular frame A and the bottom A' 55 which may be regarded as a portion of the

supporting frame, or base, of the structure. The bottom A' preferably is composed of sheet-metal. The sheet-metal member has an upturned flange 5 which fits within the frame A and is equipped with supporting 60 lugs 5^a which are bent over the upper surface of the frame A and secured thereto, as by means of nails 5^b.

If desired, the bottom A may be provided with perforations 6 equipped with inwardly 65 opening valves 6^a (one shown). These valves may be of leather secured at one point to the bottom A', as by means of a rivet 6^b. The valves open inwardly or upwardly to admit air when the cushion is distended; 70 and they close to give a pneumatic cushioning effect when the cushion is compressed.

As will be noted from Fig. 2, the main body of springs C have their upper ends projecting some distance above the outer 75 marginal row of springs B; also, by reason of the fact that the bottom A' is depressed so as to be substantially flush with the lower surface of the frame A, the lower ends of the main body of springs extend below the lower 80 ends of the outer marginal row of springs B.

The marginal row of the main body of springs C, or any desired number thereof, are connected by ties 7 with the upper end portions of the springs of the outer marginal 85 row B.

The covering E is stretched tautly over the springs and wadding D, and the skirt portions 8 of the fabrics are carried downwardly and secured to the frame A as by 90 means of tacks 9. Thus, the skirt portions of the covering furnish the usual flexible peripheral wall of the cushion.

While the outer marginal row of springs B is anchored to the marginal row of the 95 main body of springs, there is a certain independent action of the main body of springs when the cushion is occupied. This is due partly to the greater length of the main body of springs, partly to the manner in 100 which they are connected with the outer marginal row of springs, and partly to the fact that the outer marginal row of springs preferably are heavier, or stronger, than the main body of springs. Otherwise stated, 105 the main body of springs will yield readily and conform to the person, while the outer row of springs will offer more resistance and tend to give a certain desired firmness of support to the limbs near the knees. This 110

action will occur without inconvenience to the person seated on the cushion, owing to the fact that the marginal row of the inner main body of springs will yield rather readily when the person is seated. Moreover, the outer marginal row of springs tends to prevent sagging of the cushion at its peripheral portion, which is a desirable feature.

Again, the use of the two marginal rods, 10 or heavy wires, spaced in the manner illustrated, provides greater strength for the cushion as a whole, without sacrificing desired flexibility and resilience.

The improved cushion is a self-sustaining 15 structure which may be placed upon any suitable support. The improved cushion may be made of necessary length and of the right proportions to serve as a seat cushion or as a back cushion in a sleeping car berth, 20 where the advantages noted are highly desirable.

What I regard as new, and desire to secure by Letters Patent, is:

1. A cushion comprising a base, an outer 25 marginal row of upholstery springs mounted on said base, fabric coverings enclosing the individual springs of said row, an inner main body of upholstery springs mounted on said base and rising a substantial 30 distance above said outer marginal row of springs, individual fabric coverings enclosing the individual springs of said main body of springs, a marginal rod secured to the upper end portions of the outer marginal 35 row of springs, a marginal rod secured to the upper end portions of the marginal row of the main body of springs, ties connecting the upper portions of the outer marginal row of springs and the adjacent 40 intermediate portions of the marginal row of the main body of springs, stuffing material above said groups of springs, and a fabric covering enclosing the stuffing material and springs and secured to said base.

45 2. A cushion comprising a base, an inner main body of relatively light upholstery springs encased in individual fabric cover-

ings, said springs being nested in close contact with each other and connected by ties, an outer marginal row of relatively stiff upholstery springs encased in individual fabric casings contacting with each other and connected by ties, said last-named springs having their upper ends disposed a substantial distance below the plane of the upper ends 50 of the main body of springs, a marginal rod connected with the upper ends of the marginal springs of said main body of springs, a marginal rod connected with the upper ends of said outer row of springs, ties connecting the upper ends of the outer marginal row of springs with the adjacent intermediate portions of the marginal springs of the main body of springs, stuffing material above 55 the groups of springs mentioned, and a fabric covering enclosing the stuffing material and springs and secured to said base.

3. A cushion comprising a base consisting of a marginal frame-member and a relatively thin bottom secured to said frame-member so as to be substantially flush with the lower surface of said frame-member, an outer marginal row of upholstery springs mounted on said base, fabric coverings enclosing the individual springs of said outer 70 row, an inner main body of upholstery springs having their ends supported on said bottom and having their upper ends projecting a substantial distance above the upper ends of the outer marginal row of springs, 75 individual fabric coverings enclosing the individual springs of said main body of springs, a marginal rod secured to the upper end portions of the marginal row of the main body of springs, ties connecting the upper 80 portions of the outer marginal row of springs and the adjacent intermediate portions of the marginal row of the main body of springs, stuffing material above said 85 groups of springs, and a fabric covering enclosing the stuffing material and springs and secured to said base.

FRANK KASPAR.
